UNITED STATES PATENT OFFICE.

HARRISON S. TAFT, OF SEATTLE, WASHINGTON.

REINFORCED CONCRETE CONSTRUCTION.

1,150,077.

Specification of Letters Patent. Patented Aug. 17, 1915.

Application filed May 28, 1914. Serial No. 841,668.

To all whom it may concern:

Be it known that I, HARRISON S. TAFT, a citizen of the United States, and resident of Seattle, in the county of King and State of Washington, have invented new and useful Improvements in Reinforced Concrete Construction, of which the following is a specification.

My invention relates to reinforced concrete structures, and consists in improvements in the construction of concrete floors, roofs, or dock decks and the like.

In the drawings hereto annexed which illustrate my invention, Figure 1 shows, partly in elevation and partly in section, a portion of a concrete dock deck; Fig. 2 shows in perspective one of the pyramidal cells which are a characteristic factor in my improved structure; Fig. 3 shows in plan the top of a supporting column; Fig. 4 shows, partly in elevation and partly in cross-section, another form of dock deck; Fig. 5 is a plan view of the top of the pile cap shown in Fig. 4; and Fig. 6 is a diagram showing the mode of assemblage of the elements of my improved reinforced concrete platform.

Referring to Fig. 1, the numeral 1 refers to reinforced concrete piles or columns which may be of any desired internal construction and which form the sub-structure for the reinforced deck or platform. Columns 1 are surmounted by capitals 2 in which are formed end chambers 3 and recesses 5, the latter surrounded by a lip or flange 4. The reinforcement 6 of the column 1 projects upwardly into the chamber 3.

The superstructure carried by the columns 1 consists of a cellular system composed essentially of a plurality of assembled, juxtaposed, hollow reinforced concrete pyramids which are integrated with a continuous reinforced concrete floor slab which overlies the bases of the said pyramids and is incorporated with them both by the mode of molding the concrete of which the parts are composed and by the interlacing of the reinforcement of one concrete factor into another.

50 The reinforced concrete pyramids 7 are molded preferably with transverse webs 8 and 18 (see Fig. 2) and are furnished with internal steel reinforcement such as 11. The transverse webs also will be reinforced in any desired manner. The transverse webs 8 and 18 extend a little beyond the base mar-

gin 10 of the pyramids 7. The pyramids at their apices are developed into a short trunk 19. In the trunk 19 a vertical reinforcement 12 is embedded and this reinforcement projects from the trunk so that when one of these pyramidal cells is put in place upon a column head 2, the reinforcement 12 and reinforcement 6 mutually interpenetrate within the chamber 3 which will be filled with grout or equivalent cementitious matter which integrates the two members, namely, the column head 2 and the pyramidal cell 7; also, before the pyramidal cell 7 is put in place, tie beams 13 are laid in the notches 14 and extend from column to column. The notches or slots 26 in the trunk 19 will, when the pyramidal cell 7 is lowered into place, slip over the tie beams; grout poured into the recess 5 will then fill the slots 14 and 26 and firmly incorporate the tie beams with the concrete structure. When a number of the pyramidal cells 7, previously molded, have been lowered into place upon the columns 1, suitable wooden forms will then be arranged for the molding of the deck slab 9 and filler beams 15. The reinforcement 11 in the sides of the pyramidal cells 7 projects diagonally upward out of the base margin 10, and slab reinforcement 16, 17 will be incorporated into the deck slab before or at the time the latter is being molded. After the wooden molds are in place, concrete is molded thereon forming the filler beams 15 and deck slab 9. The molding of the deck slab and filler beams integrates the entire structure so that it comprises in a single substantially monolithic form an assemblage of hollow pyramidal cells with integrated adjoining base margins and a single continuous slab or diaphragm constituting a common base or cover plate for the pyramidal cells. By having the transverse webs 8 and 18 rise a little above the base margin 10, the deck slab 9 when molded and integrated with the said transverse webs, leaves space for the molding of the concrete filler beams 15 which being deeper than the deck slab 9 afford elements of stiffening and strength. 105 Any kind of flooring may be laid upon the deck slab 17 such as a wooden block flooring 25. At the outer edges of the deck slab, side beams 23 may be molded if desired and to these the side piling 24 may be attached. 110

In Fig. 4 there is shown a modification of the above described construction in which

the cellular integrated concrete structure is placed upon concrete cap blocks 22 which are molded upon pile foundation 21. In this construction the apex trunk of the pyramidal cell 7 will be flared at 20 so as to form a dovetailed joint when grouted into the recess in the cap 22. Tie beams or tie rods 27 passing through holes prepared for them in the caps 22, perform the same function 10 as the tie beams 13 of Fig. 1.

The general cellular structure diagrammatically illustrated in Fig. 6 shows how the filler beams 15 form a main latticed structure while the transverse webs 8 and 18 of 15 the pyramidal cells 7 form subordinate latticed structures, the whole affording a high power of resistance to bending under load applied in whatever direction.

The cost of construction of the cellular 20 flooring above described will be comparatively low because the pyramidal heads can be molded as separate pieces wherever convenient and when put in place will be very readily integrated with their supporting 25 columns or caps without the employment of any timber forms. The timber forms for the floor slab and floor beams will require a minimum of material and few, if any, long members, since the pyramidal cells are 30 already assembled with their base margins so close together that very little area will have to be occupied by wooden molds. The transverse webs in the pyramidal cells have 35 small areas between them which can be covered with light wooden floor slab molds, which remain in the cell-compartments after the floor slab has been formed. These small areas may be also covered with suitable steel fabric forms such as are commercially 40 known as "Hy-Rib," which will remain in the cell compartments after the floor slab has been formed.

I claim:

1. Reinforced concrete structure, comprising in combination, columns, pyramidal hollow reinforced concrete cells with their base margins adjacent to each other and their apices joined to the columns, and filler beams of concrete molded between and incorporated with the base margins of the pyramidal cells, the whole constituting a substantially continuous cellular structure. 50

2. Reinforced concrete structure, comprising in combination, columns, pyramidal 55 hollow reinforced concrete cells with their base margins adjacent to each other and

their apices joined to the columns, and filler beams of concrete molded between and incorporated with the base margins of the pyramidal cells, and reinforced concrete 60 floor slabs molded on the bases of the pyramidal cells and incorporated with the filler beams.

3. Reinforced concrete structure, comprising in combination, columns, pyramidal 65 hollow reinforced concrete cells with internal cross-webs, said cells arranged with their base-margins adjacent to each other and their apices joined to the columns, filler-beams of concrete molded between and incorporated with the base margins of the pyramidal cells, and reinforced concrete 70 floor slabs molded over the bases of the pyramidal cells, resting on the cross-webs and incorporated with the filler beams, the 75 whole constituting a substantially continuous cellular structure.

4. Reinforced concrete structure, comprising in combination, columns, pyramidal hollow reinforced concrete cells arranged 80 with their base margins adjacent to each other and their apices joined to the columns, a reinforced concrete floor slab molded on the bases of the pyramidal cells, incorporated therewith and integrating the assemblage of cells, said cells slotted near their apices, and tie beams passing through said slots and secured to the cells. 85

5. Reinforced concrete structure, comprising in combination, columns having end 90 chambers and reinforcement projecting from the shafts of the columns into said chambers, pyramidal hollow reinforced concrete cells to rest on the columns and provided with reinforcement projecting from 95 their apices, the projecting reinforcements of the columns and cells mutually interpenetrating in said column chambers, and a cementitious filling in said chambers, integrating the columns and cells; the base margins of the cells adjacent to and incorporated with each other, and a reinforced concrete floor slab covering the assemblage of pyramidal cells and integrating them into a substantially continuous structure. 100

Signed by me at Seattle, Washington, this twenty first day of May 1914.

HARRISON S. TAFT.
